US00D879135S

(12) **United States Design Patent** (10) **Patent No.:** **US D879,135 S**
(45) **Date of Patent:** **** Mar. 24, 2020**

(54) **DISPLAY SCREEN OR PORTION THEREOF
WITH GRAPHICAL USER INTERFACE**

(71) Applicant: **AMTRAN TECHNOLOGY CO., LTD**, New Taipei (TW)

(72) Inventor: **Te-Heng Wang**, New Taipei (TW)

(73) Assignee: **AMTRAN TECHNOLOGY CO., LTD**, New Taipei (TW)

(**) Term: **15 Years**

(21) Appl. No.: **29/662,624**

(22) Filed: **Sep. 6, 2018**

Related U.S. Application Data

(63) Continuation-in-part of application No. 29/593,254, filed on Feb. 7, 2017, now abandoned.

(30) **Foreign Application Priority Data**

Jan. 6, 2017 (TW) 106300104

(51) **LOC (12) Cl.** **14-04**

(57) **CLAIM**

The ornamental design for a display screen or portion thereof with graphical user interface, as shown and described.

DESCRIPTION

The FIGURE is a front view of a display screen or portion thereof with graphical user interface showing my new design.

The dot-dash broken line represents the display screen and forms no part of the claimed design. The remaining broken lines represent elements of the graphical user interface and form no part of the claimed design.

1 Claim, 1 Drawing Sheet
